UNITED STATES PATENT OFFICE.

EDWIN R. STILWELL, OF DAYTON, OHIO.

SELF-OILING JOURNAL-BEARING.

SPECIFICATION forming part of Letters Patent No. 559,956, dated May 12, 1896.

Application filed April 10, 1895. Serial No. 545,147. (No model.)

To all whom it may concern:

Be it known that I, EDWIN R. STILWELL, a citizen of the United States, residing at Dayton, county of Montgomery, State of Ohio, 5 have invented a certain new and useful Improvement in Self-Oiling Journal-Bearings, of which the following is a specification.

My invention relates to self-oiling journal-bearings.

10 The object of my invention is to provide a journal-bearing and to so construct such bearing that oil will be continuously conveyed from a reservoir therein to the top of the shaft revolving in the journal-bearing, and 15 thus provide a journal-bearing that will run for months without any attention whatever.

My invention is illustrated in the accompanying drawings, wherein—

Figure 1 is a plan view of the journal-bearing with the cap removed and with parts broken away. Fig. 2 is a vertical longitudinal section through the same. Fig. 3 is a cross-section on line 3 3 of Fig. 2.

Like parts are indicated by like letters 25 throughout the several figures.

As shown in the drawings, a shaft A is journaled in a divided journal-box B, said journal-box being supported by the pillow-block C and provided with the cap D. A wheel or 30 disk A' is connected with the shaft A so as to rotate therewith, and is located between the two portions of the divided journal-box. The pillow-block C is provided with the oil-reservoir C', and the disk A' projects into such 35 oil-reservoir. The inner ends of the portions of the divided journal-box are provided with the annular projecting flanges B' B'. These flanges are of such size and shape as to completely inclose the disk A'. Said flanges are 40 cut away below the shaft at B² B², so as to allow the oil in the reservoir C' to have free access to the disk A'. It will thus be seen that the disk or wheel is provided with an inclosing cover within the pillow-box and cover, 45 such inclosing cover communicating with the oil in the reservoir C' by the opening formed by cutting away the portions B² B². Said flanges are also provided above the shaft with the holes B³ B³, which pass through their 50 sides, as shown, and also with the opening B⁴, which passes through their outer edges. The upper parts of the two portions of the divided

journal-box are provided with the oil-holes B⁵ B⁵, said oil-holes being preferably connected by means of a groove B⁶ with the holes B³ B⁴. The holes B³ B³ are preferably used when the shaft is revolving at a low rate of speed, while the opening B⁴ is best adapted to accomplish the purpose when the shaft is revolving at a high rate of speed. 60

In order that I may control the size of these openings and thus adjust the bearing for any given rate of speed, I provide such openings with the controlling-valves, which, as shown in the drawings, consist of the screws B⁷ B⁷. 65 The oil after passing through the bearing may return to the reservoir by means of the passage-ways C² C² at the ends of the pillow-block and cap. The disk A' is preferably notched or indented on its periphery, as shown, 70 so that it may the better lift the oil out of the reservoir and force it through the openings B³ B⁴. I have described these several parts in detail; but it is evident that they may be varied in form, construction, and arrangement and that some of them may be omitted 75 without departing from the spirit of my invention.

I may also use a single continuous journal-box instead of a divided journal-box, as shown, 80 and I therefore do not wish to be limited to the exact construction set forth in the drawings.

I have shown the journal-box or babbitt-bushing as made in four pieces; but it is evident that such bushing may be made in two pieces, if desired. 85

I have described the oil-carrying disk as rigidly connected to the shaft; but it is evident that in some cases it may be desirable 90 to have the disk loose upon the shaft, said disk being rotated by its frictional contact with the shaft.

It is also evident that this journal may be adapted to any form of hanger or rigid journal. 95

The use and operation of my invention are as follows: When the parts are in the position shown in the drawings and the shaft is revolving, the oil in the reservoir C' adhering to the disk A' is thrown against the sides of the flanges B' B' and flows out through the holes B³ B⁴. It is then carried by gravitation by means of the grooves B⁶ to the openings B⁵ B⁵ in the journal-box, and is thus brought 100

into contact with the shaft, and after performing its purpose runs back into the reservoir C'. It will thus be seen that by this construction I am able to produce a self-oiling bearing 5 that carries the oil to the top of the journal box or bushing, where it is then distributed and returned to its reservoir to be again used in a similar manner. The openings B³ B³ are best adapted for slow speeds, while the opening B⁴ is used to the best advantage when the shaft is revolving at a high rate of speed, each of the openings of course being controlled by means of the screws B⁵ B⁷, so that only the required amount of oil will be supplied to the 15 shaft.

The real principle of my invention consists in the association with the rotating shaft of new and improved means or devices, which practically constitute a pump or the like, 20 whereby the oil in mass is carried up to the upper part of the shaft without being scattered around the pillow-block and cover, and means for distributing such oil along the shaft.

25 I claim—

1. A self-oiling bearing comprising a journal-box in which the shaft is journaled, a pillow-block and cover for the same, a wheel or disk connected with such shaft so as to rotate therewith, an oil-reservoir into which said disk projects, said journal-box being provided with annular projecting flanges which form an inclosing cover for the disk, within the pillow-block and cover, that prevents the 35 oil from being scattered, said inclosing cover having an opening through which the oil in the reservoir is admitted to the wheel and also having one or more openings above the shaft by which the oil may pass out through the 40 cover, means for regulating the flow of oil through said openings, the journal-box having a series of holes in its top so situated that the oil from said opening or openings will be conveyed to the shaft.

45 2. A self-oiling journal-bearing comprising an oil-reservoir, a divided journal-box in which the shaft is journaled, a pillow-block upon which said box is supported, and which is provided with a cover, a wheel or disk on 50 said shaft located between the two portions of said journal-box and projecting into said reservoir, the portions of said journal-box being provided with annular projecting flanges which form an inclosing cover for said disk, 55 within the pillow and cover, said inclosing cover having an opening through which the oil in the reservoir is admitted to the wheel, and also having one or more openings above the shaft by which the oil may pass through 60 the cover, and a series of holes in the upper part of each portion of the divided journal-box and by which the oil may be conveyed to the bearing.

65 3. A self-oiling journal-bearing comprising a divided journal-box in which the shaft is journaled, a pillow-block upon which said box

is supported, said block provided with a removable cover, a wheel or disk provided with a notched or indented periphery and connected with said shaft, so as to rotate therewith, 70 said disk located between the two portions of said journal-box and projecting into the oil-reservoir, projecting flanges on the two parts of the journal-box which form an inclosing cover having an opening through which the 75 oil in the reservoir is admitted to the wheel, and also having one or more openings above the shaft by which the oil may pass out through the cover, and a series of holes in the upper part of each portion of the divided 80 journal-box by which oil may be conveyed to the bearing, and a connecting-channel between the opening in said inclosing cover and the series of holes in the journal-box.

4. A self-oiling bearing comprising a journal-box in which the shaft is journaled, a pillow-block upon which said box is supported, said block provided with a removable cover, a wheel or disk connected with said shaft so as to rotate therewith, an oil-reservoir into 85 which said disk projects, an inclosing cover for said disk, within the pillow-block and cover, that prevents the oil from being scattered, said inclosing cover having an opening through which the oil in the reservoir is admitted to the wheel, and also having one or more openings above the shaft by which the oil may pass out through the cover, and a series of holes on the top of the journal-box so 90 situated that the oil passing through said 100 opening or openings will be conveyed to the shaft.

5. In a self-oiling journal-bearing the combination of a shaft with a pump-like apparatus associated therewith and driven thereby 105 and adapted to carry the oil in mass above the shaft said pump-like apparatus contained within the journal-box, and channels or ways for conducting and discharging the oil along the upper part of the shaft said channels 110 formed by cutting away part of said journal-box, and means for controlling the outflow of the oil.

6. In a self-oiling journal-bearing the combination of a shaft with a journal-box therefor, a rotating wheel on the shaft inclosed within said journal-box, said journal-box forming a case surrounding the wheel, whereby it acts as a pump to carry the oil from the reservoir below to the upper part of the shaft, 115 said case having escape or conducting channels or passages whereby the oil is discharged upon and distributed along the shaft said escape-passages being provided with controlling devices at one end and communicating 120 with the shaft at the other end substantially 125 as described.

Signed at Dayton, Ohio, March 27, 1895.
EDWIN R. STILWELL.
